UNITED STATES PATENT OFFICE.

SAMUEL BRAND, OF ROCKFORD, ILLINOIS, ASSIGNOR, BY MESNE ASSIGNMENTS, TO HOWARD D. COLMAN, LUTHER L. MILLER, AND HARRY A. SEVERSON, COPARTNERS TRADING AS BARBER-COLMAN COMPANY, OF ROCKFORD, ILLINOIS.

ARTICLE-POSITIONING MEANS.

1,095,977.

Specification of Letters Patent.

Patented May 5, 1914.

Application filed August 28, 1907. Serial No. 390,446.

To all whom it may concern:

Be it known that I, SAMUEL BRAND, a citizen of the United States, residing at Rockford, in the county of Winnebago and 5 State of Illinois, have invented certain new and useful Improvements in Article-Positioning Means, of which the following is a specification.

This invention relates to means for placing articles in a predetermined position.

One object of this invention is to provide means for presenting articles with uniformity to a point of discharge.

Another object of the invention is to provide means whereby a particular end will always be foremost in going through a discharge.

I have herein shown the invention as adapted for receiving a number of bobbins 20 and means is disclosed for selecting and insuring that the tip end of the bobbin will always be presented foremost through a discharge opening in the receptacle.

The present embodiment of the invention 25 is in the nature of an accessory to spoolers, winders and other machines which operate upon bobbins containing filling yarn or yarn warp.

In the accompanying drawings, Figure 1 30 is a top plan view of an apparatus embodying my invention; and Figs. 2 and 3 are side elevations thereof, partially in section.

The present embodiment of my invention 35 comprises a framework 1, in the upper part of which is an entrance or inlet passage 2 for the bobbins *a*, the latter being placed in said passage by any suitable means. In the lower part of the frame is the discharge chute 3.

40 The bobbin-positioning device comprises a drum 4 mounted upon a shaft 5 supported in the frame 1, said shaft having a drive pulley 6 fixed thereto. The drum 4 is provided with a peripheral series of bobbin-pockets formed in this instance by trans- 45 verse partitions or flanges 7 rigidly mounted upon its periphery. The drum 4 and the inlet passage 2 are so disposed with reference to each other that the bobbins will be delivered singly into the bobbin-pockets a little to one side of the highest point in the periphery of the drum. In the present instance the bobbin-pockets are wide enough 50 to permit of a slight amount of movement

of the bobbins around the drum 4 as the latter is rotated to carry the bobbins past said highest point. From a point somewhat above the horizontal center of the drum to the upper end of the discharge chute 3 the outer sides of the bobbin-pockets are closed 60 by a curved guard plate 8 fixed in the frame 1.

To each side of the drum 4 is secured a radiating series of spring arms 9, each provided with a pin 10 adapted to enter the 65 opening in the head end of the bobbin, but too large to pass into the smaller opening in the tip end of the bobbin. In the upper part of the framework 1 at each side of the drum 4 is a stationary cam 11 adapted to 70 force the spring arms 9 outward, said cam extending from a point somewhat in advance of the inlet passage 2 to a point about sixty-five degrees past the highest point in the periphery of the drum. The pins 10 75 are of such length that when one of them lies in the opening in the head of the bobbin, the other does not press against the tip end of the bobbin, but merely prevents any considerable endwise movement of the bobbin. 80

In operation, the drum 4 is rotated and the bobbins fed through the inlet passage 2 by any suitable means adapted to deliver one bobbin to each bobbin-pocket. The cams 11 hold the spring arms 9 bent outwardly throughout the greater portion of their travel above the horizontal plane of the center of the drum. When a bobbin in the rotation of the drum 2 is carried slightly past the highest point of the periphery of 90 the drum, said bobbin rolls downward against the forward flange 7, in which position it lies with its ends in proper position to be engaged by the spring arms 9 when the latter are permitted to return to their inward normal position by the cams 11. The pin 10 carried by one of said spring arms then passes into the axial opening in the head end of the bobbin. The bobbin is rotated in this position until it reaches the 95 discharge chute 3, when the smaller end of the bobbin swings downward, as indicated in Figs. 2 and 3, the pin engaging the head end of the bobbin serving as a pivot for the bobbin, or in other words, causing the 100 bobbin to turn as it falls from its pocket. It will thus be seen that the bobbins are delivered from the drum 4 into the dis-

charge chute 3 tip end first, without regard to their position when placed in the inlet passage 2.

It is evident that movable carriers of other forms may be substituted for the drum 4, that the bobbins might be discharged at an earlier point in the rotation of the drum, that the head end of the bobbin might be engaged otherwise than pivotally, and that the apparatus may be adapted to operate upon various articles, without departing from the spirit of the invention.

I claim as my invention:

1. Bobbin-positioning means comprising a rotatory member adapted to carry bobbins with their ends toward the sides of said member, and pins at each side of said member adapted to enter the lower end of each bobbin.

2. Bobbin-positioning means comprising a rotatory member having a peripheral series of bobbin-pockets adapted to contain bobbins with their ends toward the sides of said member, a radiating series of spring arms secured to each side of said member, pins on said arms adapted to enter the head ends of the bobbins, and a stationary cam for forcing said spring arms outward into inoperative position.

3. A receptacle for receiving bobbins provided with tips and heads, the heads of some of the bobbins being in alinement with the tips of adjacent bobbins, and means for selecting the tip of each bobbin irrespective of the position of the bobbin and causing said tip to be passed foremost through the receptacle.

4. A bobbin positioning means comprising a rotatory member having a series of bobbin pockets; and means at each side of each pocket movable into and out of operative position to engage a certain end of the bobbin in a pocket.

5. A bobbin positioning means comprising a rotatory bobbin carrier; and means at each side of said carrier to engage the head end of each bobbin.

6. Means for handling bodies having differently constructed ends, comprising means for receiving such bodies, and two series of oppositely disposed resiliently-supported devices each adapted to engage a certain end of such a body, said series being located at opposite sides of said receiving means so that the bodies lie between the two series, the space between two opposed devices of said series being only sufficient to receive a

single body, and either of said opposed devices being adapted to engage said body, all of said end-engaging devices being similar and being movable into and out of engaging position.

7. Bobbin-positioning means comprising a rotatory member having a peripheral series of bobbin-pockets adapted to contain bobbins with their ends toward the sides of said member, resiliently supported means carried by said member and adapted to engage a certain end of each bobbin, a stationary cam for forcing said engaging means outward into inoperative position, and stationary means for closing the outer sides of said pockets during a portion of their travel, the bobbins falling from said pockets when rotated past said closing means, and swinging downwardly on the resiliently supported means.

8. Bobbin-positioning means comprising a part on which bobbins may be supported, and movable members carrying pins adapted to enter the head ends of the bobbins, said members being arranged at opposite ends of bobbins supported on said part, the bobbins falling from said supporting part when moved off said part, and swinging downwardly on the pins engaging the head ends of said bobbins.

9. Bobbin-positioning means comprising a part on which bobbins may be supported, and movable members carrying devices adapted to engage a certain end of the bobbins and not adapted to engage the opposite end of the bobbins, said members being arranged at opposite ends of bobbins supported on said part, the bobbins falling from said supporting part when moved off said part, and swinging downwardly on the devices engaging said certain ends of the bobbins.

10. Bobbin-positioning means comprising a rotatory member having a single peripheral series of bobbin-receiving pockets, said pockets extending transversely of the rotatory member so as to carry the bobbins with their ends toward the sides of said member, spring arms moving with said member at each side of the latter, bobbin-pivoting means on said arms for engaging one end of each bobbin, and means for holding said arms in inoperative position through a part of the rotation of said member.
